UNITED STATES PATENT OFFICE

164,757

ADVERTISING DISPLAY FIGURE

Maylock Artmann, New York, N. Y., assignor to
C. Schmidt & Sons, Inc., Philadelphia, Pa., a corporation

Application December 9, 1949, Serial No. 6,518

Term of patent 14 years

(Cl. D1—2)

To all whom it may concern:

Be it known that I, Maylock Artmann, a citizen of the United States, residing in New York, Bronx County, New York, have invented a new, original, and ornamental Design for an Advertising Display Figure, of which the following is a specification, reference being had to the accompanying drawing, forming a part thereof.

Fig. 1 is a front perspective view of an advertising display figure showing my new design. Fig. 2 is a left side view of the figure. Fig. 3 is a rear view of the figure.

I claim:
The ornamental design for an advertising display figure, as shown.

MAYLOCK ARTMANN.
